UNITED STATES PATENT OFFICE

2,564,817

GUIDED JAW NIPPERS

John D. Sammons, Orla, Tex., assignor of one-half to Robert E. Cunningham, El Paso County, Tex.

Continuation of application Serial No. 611,803, August 21, 1945. This application February 16, 1951, Serial No. 211,331

1 Claim. (Cl. 30—186)

1 This invention constitutes a continuation of my pending application Serial No. 611,803, filed August 21, 1945, now abandoned, for hand tool and appertains to improvements in tools employed for repairing and maintaining wire fences and other wire structures.

The primary object of the instant invention is to provide a hand tool, which is equipped with means for carrying out the various operations, attendant with the erection of wire fences and the construction of other wire structures, the tool being provided with an improved claw hammer, a wire cutter and wire puller facilities of extremely simple and efficient construction and arrangement.

These and ancillary objects and structural features of merit are attained by this invention, the preferred embodiment of which is set forth in the following description and illustrated in the accompanying drawing, wherein:

Figure 1 is a side elevational view of a tool, constructed in accordance with the principles of this invention;

Figure 2 is a top plan view of the tool, with the movable parts in closed position;

Figure 3 is a fragmentary longitudinal sectional view taken on line 3—3 of Figure 1;

Figure 4 is an end elevational view of the head portion of the tool;

Figure 5 is a fragmentary top plan view of the tool, with the movable parts disposed in an open position;

Figure 6 is a fragmentary sectional view taken on line 6—6 of Figure 1;

Figure 7 is a transverse sectional view taken on line 7—7 of Figure 1, and,

Figure 8 is a fragmentary view, illustrating one of the claw members of the head, provided with a bulged portion for removing staples.

Referring now more particularly to the accompanying drawing, the tool includes a handle portion 10, which may be formed in various desirable lengths. As illustrated, the handle portion includes a pair of complementary longitudinal half sections 11, 11', which are hingedly connected together, at one end, as at 12. The pivotal attachment of the handle sections 11 and 11' is preferably detachable and is effected by means of a shouldered screw or pivot stud 13, the head portion of which is recessed for the application of a conventional Allen screw wrench. The head of the pivot stud is countersunk in the adjacent portion of one of the handle sections and the screw threaded shank of the stud terminates at a point to be at least flush with the outer face 55

of the opposite handle section. In this manner, interfering protrusions on the opposite faces of the handle portion 10 are eliminated, at the region of the pivot.

2 The handle section 11 is formed, at the pivoted end thereof, with a flat upper portion of reduced thickness, that is, of substantially longitudinally half section, the portion 14 forming a circular bearing disc and being disposed at right angles to the inner and outer surfaces of the handle and offset laterally from the inner surface thereof. A similar flat bearing member or disc portion 15 is formed on the adjoining end of the complementary handle section 11' and the portion 14 rotatively overlaps the offset portion 15 of the handle section 11', with the offset bearing member or portion 15 being directed laterally from the inner surface of the handle section 11'. The portions 14 and 15 receive the pivot stud 13, which is transversely disposed therethrough and which retains the bearing portions in vertical alignment, with their adjoining surfaces being in rotative engagement. The bearing member or disc portion 15 projects from the lower part of the handle section 11, while the bearing member 14 projects from the upper part of the handle section 11', the handles having arcuate edges 16 and 17 engageable with the surfaces of the bearing members or disc portions to provide a limited hinge movement between the handle sections 11 and 11'.

The handle section 11 is provided with a jaw extension 19, the jaw extension being formed integral with the bearing member 14 and projecting upwardly from the outer portion of the periphery of the portion 14. The jaw extension terminates at its upper end in a prong 18, adapted to form one part of a claw structure. The lower or opposite end of the jaw extension depends below the bearing member 14 and is disposed at right angles thereto, the end being flat and defining a flat shoulder. The shoulder is disposed transversely to the pivot stud and parallels the contacting surfaces of the portions 14 and 15.

The bearing member or disc portion 15 of the handle section 11 is provided with an integral jaw portion or extension 24, which is disposed at right angles thereto. The jaw extension 24 is formed integral, at its lower end, with a hammerhead or peen 20, which is in the form of an enlargement and which projects laterally from the inner face or surface of the jaw extension. The hammerhead tapers downwardly to merge in a reduced neck portion 21 and is flared outwardly to terminate in a shouldered flange 22. As shown,

the neck portion of the hammerhead or peen is provided with a plurality of rounded or elliptical notches 23 of shallow depth, the peripheral notches being provided for holding wire portions looped about the neck portion, when the tool is employed in a wire pulling operation.

It will be noted that the hammerhead projects laterally from the jaw 24 and has an upper shouldered portion 26. The hammerhead, defined by the cooperating jaw extensions, the lower end of the jaw 19 slidably engaging the shoulder 20, when the jaws are in closed positions, as seen in Figure 4, serves as a conventional nail driving member. In the closed position, the handle sections are in abutting relation and the flat end of the jaw 19 engages on the shoulder 26, formed on the inner or upper end of the lateral projecting portion of the enlargement. As shown, the jaw extension 24 is provided at the end, opposed to the hammerhead 20, with an integral upstanding prong 25, which is cooperatively arranged with the prong 18 to form a conventional claw structure.

The prong 25 and the prong 18 are adapted to be arranged in confronting positions, with the complementary jaw extensions adapted to mate, the shouldered portion 26 underlying and contacting with the end of the jaw extension 19. The jaw 18 rests on the shouldered portion 26 and the outer surface thereof is flush with the outer surface of the hammerhead or peen, so that when the handles are closed, the head portion resembles a conventional claw hammerhead. When the handles are closed, the hammerhead may be utilized for nail driving purposes, the inner portions of the handles being in engagement with the force of the handle 11 being transmitted through the jaw 19 to the hammerhead, which is formed integrally with the handle 11. In the closed position of the handles 11 and 11', the prongs 18 and 25 are spaced apart, as in an ordinary claw hammer structure and the parts are, accordingly, utilized in a conventional manner.

The opposed parts of the forward meeting edge portions of the jaw extensions are sharpened, as at 29 and 30, so that cooperative cutting edges are provided on the inner confronting longitudinal edges of the jaw extensions. The cutting edges are formed integrally with the jaw extensions and, accordingly, they are hardened, tempered and sharpened.

In utilizing the tool for cutting wires, the wires are inserted between the jaw extensions, with the handle sections in an open position and the jaw extensions swung apart. The handles are then brought together, with their inner faces moved into abutting relation, and the handle extensions are moved together, so that the cutting edges 29 and 30 are moved, under force, through the wires, interposed between the jaw extensions. It will be especially noted that the lower flat end of the jaw extension 19 is slidably disposed on the shoulder 26, so that the enlargement forms a guide for the jaw which moves relative to the jaw extension 24. If desired, the jaw extension 24 may be held rigid and in a vertical position, the jaw extension having the free end of the enlargement or hammerhead resting on a horizontal supporting surface. In such position, the wire is inserted between the jaw extensions and the jaw extension 18 is moved relative to the jaw extension 25, which forms a guide therefor.

For the accommodation of the wires and the cutting thereof, the meeting portions of the base

extensions 18 and 25, the flattened and reduced end portions 14 and 15 of the handle sections 11 and 11' and the lug member 19 and jaw extension 24 are recessed to provide an opening 31 between the parts, the opening 31 paralleling the cutting edges 29 and 30. It will be noted that the cutting edges are disposed parallel with the pivot element and are arranged transversely to the engaging surface of the hammerhead, so that when the device is used as a hammer, the force exerted on an object by the hammerhead does not impose any strain on the cutting edges nor does it effect any rubbing or digging contact of the cutting edges. Furthermore, it will be noted that the cutting edges, pivot element and jaw extensions have parallel axes and are disposed in the same plane, when the cutting edges are in contact, the cutting edges contacting when the handle sections are swung about the pivot element to bring the inner faces thereof into abutting relation.

The forward meeting edge portions of the lug member 19 and the jaw extension 24 of the handle section 11' are recessed to provide a pair of vertically aligned openings 32 and 33 and between these openings, the parts 19 and 24 are provided with tapered bulges 34, whose meeting edges are sharpened, as at 35, to provide staple-puller projections.

The handle sections 11 and 11' may be of any suitable construction and cross-sectional form in the body thereof. As shown in Figure 2, and more clearly in the cross-sectional view in Figure 7, each of the handle sections 11 and 11' has a flattened portion 36 substantially elongated throughout the grasping portion of the tool, the part 36 being formed integrally with the forward portion of each handle section and the same is covered by a correspondingly elongated segmental member of wood or a suitable plastic material. As shown more clearly in Figure 7, the covering members 37 are formed with rounded outer faces for convenience in grasping and handling the tool, and, preferably, the upper and lower edge portions of the flattened parts 36 of the handle sections 11 and 11' are rounded, as at 38, to avoid the production of any meeting sharp edges between which the hand of the user might be pinched in the squeezing of the tool handle sections 11 and 11' together in the use of the tool.

The covering members 37 may be attached to the parts 36 of the handle sections by any suitable means. As shown, the members 37 are riveted to the parts 36, as at 39, and the outer and inner end portions of the respective rivets are at least countersunk flush within the parts 36 and 37 so as to avoid the production of any protuberances on the faces of the parts. It is further preferable to provide on the inner face of the flattened portion 37 of one of the handle sections a dowel pin 40 which enters a correspondingly positioned recess 41 in the other handle section in the closed position of the sections as shown in Figure 2. This is to provide an effective lock to prevent independent torsional movement of the respective handle sections 11 and 11' independently of each other when in their closed position.

The combination tool of the present invention is of simple and compact yet strong and durable construction and the same is conveniently manipulated and handled by the user in various operations such as nailing, stapling, withdrawing nails and staples, the cutting of wires and the twisting and stretching of wires in fence build-

ing and maintenance, as well as in numerous other uses.

The illustrated structure is but one practical exemplification of the invention and the same admits of considerable modification within the spirit and scope of the invention as defined by the appended claim. The invention, therefore, is not limited to the specific construction and arrangement shown.

Having thus described this invention, what is claimed is:

A wire tool comprising a pair of complementary handle sections having inner flat abutting faces, each of said handle sections being formed at one of their adjoining ends with flat integral bearing members, said bearing members being arranged at right angles to said flat abutting faces and projecting laterally therefrom and being arranged in overlapping rotative engagement, a pivot element connecting the bearing members and disposed transversely therethrough, complementary first and second jaw sections integrally formed with the bearing members and disposed at right angles thereto, the first jaw section extending longitudinally beyond the second jaw sec- 25

tion at one end, an enlargement formed on the said end of the first jaw section and extending laterally from the inner surface thereof to define a flat lateral shoulder at its inner end, the second jaw section having a flat end engaging said shoulder which forms a guide for the second jaw section, the jaw sections having inner longitudinal cutting edges, said cutting edges being disposed parallel to the pivot element, and the cutting edges, pivot element and jaw sections having parallel axes and being disposed in the same plane, when the edges are in contact, the cutting edges contacting each other when the handle sections are swung about the pivot element to bring the inner faces thereof into abutting relation.
